SHEET FOLDING MACHINE

Robert L. Sjostrom, Andover, Mass.

Application March 16, 1948, Serial No. 15,065

20 Claims. (Cl. 270—84)

11

The present invention relates to a machine for folding flexible sheets such as cloth, paper, and fabrics, but finds its particular application in the folding of bed sheets, pillow cases, towels and the like in the textile industry and in folding of laundered clothes, sheets, fabrics, and the like.

In the present invention, the article to be folded is fed by means of a conveyor belt over the folding table wherein plates are moved in from the sides laterally in timed relation to effect a longitudinal fold in the manner that may be desired. The machine of the present invention may be used to make a single fold, a fold in three sections by means of a longitudinal fold from each side, a three-layer fold by means of a longitudinal fold only on one side, a fold of each side to the center, and many other types of folds as may be desired. Subsequent to finishing the longitudinal folding, which may be accomplished with or without stopping the conveyor belts, the material is conveyed through the rest of the machine wherein lateral folds as desired are made in the material.

In the prior art, the folding is accomplished by means of guiding the edges or sides of the material through channels or guides somewhat in the manner that the hemmer of a sewing machine operates. Here, however, the fold is positively made by actively turning the material by the use of moving elements, particularly plates which operate positively and entirely independently of the feed of the material through the machine. While the machines of the prior art must thread or guide the material in the folding samples, in the present invention the feed to the folding board is a simple straight feed, and all that is necessary is to present the sheet laid out flat as it comes on the folding table. The feed may be accomplished in any way desired although the manner herein illustrated is preferred and has its advantages and the machine can be operated by one operator, if a manual feed is used, or, if an automatic feed is used, one operator can operate a bank of machines. Other advantages and features of the invention will be understood from the description in the specifications below when taken in connection with the drawings illustrating an embodiment of the invention, in which:

Fig. 1 shows a side section in elevation of the 50 forward part of the machine on the line I—I of Fig. 2:

Fig. 2 shows a plan view of the same forward end of the machine shown in Fig. 1;

Fig. 3 shows a section taken on the line 3-3 of Fig. 1;

Fig. 4 shows a section taken on the line 4-4 of Fig. 2;
Fig. 5 shows a section taken on the line 5-5

Fig. 5 shows a section taken on the line 5—5 of Fig. 4;

Fig. 6 shows a section taken on the line 6-6

Fig. 7 shows a top plan view of the back portion of the machine continuing from the line of Fig. 2.

Fig. 8 shows a sectional elevation on the line 8-8 of Fig. 7;

Fig. 9 shows a detail of a stop mechanism used to stop the movement of the sheets during the folding;

Fig. 10 shows a detail of switches operated by the mechanism;

Fig. 11 shows an electric wiring diagram for the operation and control of certain elements in the system;

Fig. 12 shows a modified detail which may be used in the present invention;

Fig. 13 shows a side elevation of a detail and, Fig. 14 shows a front elevation of the same detail.

The machine has an elongated frame 1 (as indicated by Figs. 1 and 2) of general rectangular section. At the left end of the machine (as

viewed in Figs. 1 and 2) there is mounted on the frame a roller 2 carried by a shaft 3 extending laterally across the frame and journalled at bearings 4, 4 at each side. The central portion of this section of the machine is provided with a plate 5 which extends up to the roller 2 but is lower than the top tangential surface. In a plane above the surface of the plate 5, at either side thereof, is a group of comparatively narrow conveyor belts 6, 6, 6, etc. on one side and 7, 7, 7, etc. on the other side. These conveyor belts form a conveying surface slightly above that of the plate 5. The conveyor belts pass over a second roll 8 and return to the roll 2, the conveyor belts

roll 6 and return to the roll 2, the conveyor belts moving in the direction shown by the arrow 9. Before the position of the second roller 8, a supporting stand 10 is mounted on the frame 1. This supporting standard is provided with a cross brace or bridge 11 having a flat flange or shelf 12, on which spring fingers 13, 13, etc., and 13', 13', etc., are mounted. These spring fingers are located between the conveyor belt strips, preferably between each of the belt strips. They are further sloped upwards to a point at 14 sufficiently high to deliver the material or sheet in the section where the fingers are on the plates 15 and 16.

50 The fingers 13 raise the material sufficiently to permit it to slide over the plate 16, while the fingers 13' permit the other section of the material to slide over the plate 15. The plates 15 and 16, as will be seen later, are at different levels.

55 Between the normal side positions of the plates 15 and 16 and at a lower level than either is a central plate 17 which is supported from the bridging frame 18. This bridging frame, as indicated in Fig. 1, may be formed as a part of 60 the supporting standard 10 and comprises a ver-

tically positioned cross plate 19 with a horizontal plate 20, forming a right angle element, both extending across the entire frame of the machine. The horizontal plate 20 carries the light source 21 of a photo electric system, which will be explained later. The vertical cross piece 19 has attached to it one end 22 of the plate 17, which is curved upwards from the flat portion of the plate as is indicated by the section 23. The material of the plate is sufficiently thin and has sufficient spring therein so that the flat section of the plate hangs flexibly from its support. The plate 17 bears by its own weight lightly on a centrally positioned conveyor belt 24, which at the forward section of the machine is wrapped about the roller 8 (see Fig. 1) between the sections where the narrow conveyor belts are positioned. The belt 24 extends in the opposite direction, however, from the conveyor belts 6 and 7, but moves in the same direction as the strips 6 and 7 as indicated by the arrow 25. The belt 24 is a continuous belt passing about a second roller 26 and returning to roller 8. The plates 15, 16, and 17 are preferably of the same length or nearly the same length and the material as it comes from these plates passes over the top surface of the plates 15 and 16 and beneath the lower surface of the plate 17 lying in frictional contact with the belt 24. When the material has been brought to the beginning of the plates 15, 16, and 17, the belt 24, moving at the same speed approximately as the belt strips 6 and 7, continues to carry the material along the machine. When both the forward and the rear edges of the material are on the plates 15, 16, and 17, the plates 15 and 16 move laterally from the sides in a manner which will presently be described to accomplish the folding of the sheet. As indicated more fully in Figs. 4, 5, and 6, the spring pivoted plate 17 is at the lowest level, the plate 15 being at the next level, and the plate 16 at the top level. The plate 15 is reinforced by a cross bar 27 attached to the plate 15 and extending in a longitudinal direction of the machine. This plate at its end carries two bearing sleeves 28 and 29, which have a good sliding fit on the cross rods 30 and 31 supported at their ends to the frame 1 of the machine. By means of this mounting, the plate 15 may move laterally part way, substantially to the center or beyond the center of the machine within wide limits of motion. The plate 16 is similarly supported by means of bearing sleeves 32 and 33 on the same rods 30 and 31, the bearing sleeves being in each case at the extreme side so that in the motion provided for by the plates the sleeves will not interfere with each other.

A crank link motion is provided for each of these plates, two vertically positioned rotatable shafts, Fig. 4, 34 and 35 which are driven in the correct phase for the desired operation as will be explained later, are permanently attached to the crank arms 36 and 37 respectively, which crank arms form the first of a pair of links pivoted to the tables respectively. The arm 37 is pivoted at 38 to the link 39, which at its other end is pivoted in the piece 40 attached beneath the plate 16. Similarly, the arm 36 is pivoted by means of the pivot 41 to the link 42, which is pivoted by means of the pivot 43 to the plate 15. Rotation of the shafts 34 and 35, therefore, will reciprocate the plates 15 and 16 between definite end limits. The movement of these plates is controlled in such a manner that the lower one of the two, 15, moves laterally inward practically to

the end of its inward motion before the upper plate of the two, 16, moves laterally inward over the plate 15. As the plate 16 moves inward over the plate 15, the plate 15 is withdrawn at about the same rate that the plate 16 moves inward. In this arrangement, the plate 15 will fold over one side of the material about the plate 17, the plate 16 will fold over the other side of the material about the other edge of the plate 17 but over the material folded by the plate 15. This type of fold can be used to make a triple or a four-folded sheet. If the material is of such a width that the plate 15 folds only one-half of the side section, so that the other half of the same side section remains on top of the plate 15 in its straight inward position, then as the plate 16 turns over the edge from the other side, a sheet with four folds will result. A sheet with two, three, or four folds can be made with this type of machine, as desired.

Means are provided by operations of a motion stop solenoid 66 (Figure 9) to stop suddenly the forward motion of the sheet while the folding occurs. When the sheet is raised slightly by the action of the side plates or when the tension of the center plate on the central conveyor belt is relieved in the folding, the stop solenoid and its mechanism may be dispensed with but for the most part it is a useful mechanism. The mechanism is shown in Figs. 1, 3, and 9. A cross support 93 extends across the frame 1 just before the roll 8. This cross support carries the stop solenoid 66 which, through its core 110, raises a bar 111 attached by an adjusting screw 112 to a link connected to the end of the core. The bar 111 carries two vertical rods 113 and 114 which pass through vertical sleeves of holes in the beam or support 93, the rods carrying the cross clamp bar 115 which may have a soft cover, or rubber edge on its top which is brought against the underside of the cloth lying beneath the plate 17, when the solenoid acts or is operated. A pair of coiled springs in position about the rods 113 and 114 between collars 116 and sleeves 118 are slightly compressed by the operation of the solenoid and return the bar quickly to its normal inoperative position after the solenoid is de-energized. The solenoid remains energized, however, during the whole folding operation and does not open until the switch 90 is momentarily opened as will be seen later.

The shafts 34 and 35 are operated through a motor drive chain and clutch system. A driving motor 46 drives through a sprocket chain 47 a reduction gear unit 48 which through a pair of beveled gears 49 and 50 rotates the upright shaft 51 on which another sprocket gear 52 is mounted, which drives through the chain 53 a second sprocket gear 54 which is pinioned to the shaft 55. The two shafts 51 and 55, therefore, drive together continuously and rotate the clutch collars or sleeves 56 and 57 respectively, to which the other halves of the clutch, 58 and 59, respectively, are connected in certain timed relations in the manner about to be described. The lower clutch collars 56 and 57 are pinned permanently to the drive shafts 51 and 55. The upper collar 58 carries a vertical pin 60 positioned in a key-way 61 (Figure 6). The pin 60 is recessed at the top to receive the spring 62 which tends to force the pin downward against the detent or holding finger 63. A press fit sleeve 45 extends around the collar 58 and keeps the pin from falling out of the key-way. When this detent is released, the pin 60 drops into the recess 64 in the lower clutch

collar 56, and thereupon the upper clutch collar turns for a time with the drive shaft 51. The upper clutch collar is permanently locked or pinned to the shaft 34 by means of the pin 65, so that the shaft 34 is turned when the collar 58 is turned. The member 63 is swung out of contact with the collar 58 when the solenoid 66 (Figs. 4 and 5) operates to pull downward the shaft 67 (Fig. 4) by means of which the bell crank lever 68 is operated. The bell crank lever 68 bears against the arm 69, which forms a part of the lever 70 pivoted at 71, which lever also carries the detent or finger 63 at its other end. A spring 72 holds the end 69 of the lever 70 in contact with the bell crank lever 68 and also keeps the detent 63 in the collar or groove in the clutch 58. When the pin drops into the recess 64 in the collar 56, the shaft 34 will turn as stated above.

This shaft 34 carries a cam 73 which rotates with the shaft 34 and causes the operation of the arm 74 pivoted at 75 to a bracket or support 76 extending from a part of the frame. The arm 74 has linked to it at its other end a rod 77 freely pivoted to the bar or arm 74 in the pivot 78. This rod 77 extends laterally across the machine and operates at its further end an arm 79 somewhat similar to the arm 74. This arm 79 carries a projection 80 and is pivoted at its other end in the pivot 81 and spring tensioned by the spring 82 so that the projection 80 normally seats in the groove 83 in the upper clutch 59 pinned to the shaft 35 by the pin 84. When the projection 80 of the arm 79 rides in the groove 83, the key or pin 85 (Fig. 5) is in its upper position and the shaft 35 does not turn. When, however, the cam 73 operating against the arm 74 rotates the lever 79 as viewed in Fig. 5 in a clockwise direction, the pin 85 will be forced downward by the spring 86 and the shaft 35 will turn. The operation of each shaft is usually set for a single revolution. The shaft 34 will turn according to the operation of the solenoid and the shaft 35 will turn at a certain time later depending upon the position of the cam 73. The cam 73 is positioned to accomplish the desired relation of operation in respect to the plates 15 and 16. When the plates operate through one revolution, the operating crank arms 36 and 37 will, of course, go through a single cycle, and so also the connecting links 39 and 42. In a normal three-fold operation, the plate 15 will move across the fixed plate 17 about to the end at the time that the plate 16 begins to move inward from its side, so that the plates 16 and 15 will be simultaneously moving to the right for the last part of the motion of the plate 15.

Nothing has been mentioned as yet with respect to the means by which the controls are operated. This may be accomplished through relay operating devices, either of the contact type or of the photo-electric type. In Fig. 1 there is shown a light source 21, which casts a beam 87 against a photo electric cell device 88.

Before describing the rest of the machine which relates to transverse folding, the system of control for longitudinal folding will be described.

As the sheet intercepts the light source 87, the circuit to the photoelectric relay 88 is closed. Power 100 is normally supplied to the terminal panel 101 at the terminals 1', 2', 4' and 7', so that closing photorelay 88 places power across the terminal 6' which connects to the relay coil 102 and to the terminal 4', thus energizing the coil 102 causing the arm 103 to leave the contact 105 and connect to contact 106. This causes the relay coil 106 to be energized between 4' and 7' and

causes both contacts 108 and 109 to close. While contact 109 is closed, no current passes through this connection because the switch arm 103 is thrown to the right in contact with 105 and out of contact with 104 as long as the sheet intercepts the beam causing the coil 102 to hold the arm. All relays here are spring returned. The coil 106 is also maintained in a closed circuit through the contact 108, the terminal 3', the restoring switch 90 to the terminal 7' so that when the light beam 87 again shines on the photocell 88 this circuit still remains closed. The arm 108, however, immediately flies back because when the beam hits the cell 87, the current in coil 102 is broken. The circuit is made from terminal 5' through the contact 109, the contact 104, the arm 103, the terminal 7' for the clutch solenoid 66 and the motion stop solenoid 66', which have one side connected to terminal 5' and the other side to terminal 4'. The clutch solenoid 66 operates to commence the movements of the tables inward, the first table 15 by its motion causing the limit switch 91 to open, thus breaking the current of the clutch solenoid 66, but still keeping the circuit of the motion stop solenoid 66'. The tables complete this motion as has been explained, for the cycle after the pin 60 is permitted to drop; and at the end of the cycle the switch 91 is restored to a closed position but not before the restoring switch 90 has been momentarily opened de-energizing the coil 106, restoring contacts 108 and 109 to an open position. The switches are then in the positions indicated in Fig. 11, which is before the beginning of the cycle of operation for the longitudinal folding.

After the solenoid 66 has released the folded piece, the belt 24 draws the sheet to the right (Figs. 7 and 8) to the transverse folding mechanism. A second roller 120, which may have a rubber cover, bears against the roller 26. This roller is journaled at each side of the machine to pivoted arms 121 pivoted at 122. A spring 123 tensions the roller 120 to the roller 26, and a chain drive 124 is so connected through sprocket gears 126 and 126' attached to the ends of the roller shafts that the roller 120 moves in opposite rotation to the roller 26. The roller 120 is covered by a plate 125 so that the sheet will first pass over the roller 120 without being drawn between the two rollers. After the sheet has gone beyond the roller 120, it is picked up by the conveyor belt 127, which is linked around the roller 128, positioned just beyond the rollers 120 and 129 near the end of the machine. The belt 127 continues the travel of the sheet until the sheet hits the projecting arm 129' controlling the switch 130 which operates the solenoid 131 pulling the core 132 and the link 133 attached to the arm 134 which projects from the arm 136 pivoted at 135 on the same pivot as the bar 137. The arm 134 at its other end carries the thin plate 138. The arm 134 swings when the solenoid operates so that the plate 138 forces the sheet spanning the belt 24 and plate 125 down between the rollers 26 and 120 folding the sheet as desired. The switch 130 may be moved along the bar or bracket 139 to any position in accordance with the fold desired.

Beneath the rolls 26 and 120 is another series of rolls 140 and 141, about which travels the conveyor belt 142 moving in the direction of the arrow 143. The sheet which comes down between the rollers 26 and 120 drops on this conveyor belt and is carried to the right (Fig. 8).

on to the plate 144 covering the top of the roll 145. The sheet then comes in contact with the belt 146 traveling around rollers 157 and 158 in the direction of the arrow 147, and is carried until it trips the arm 148 of the switch 149 attached by arm 159 to the bracket 151 which can be adjusted on the support 152. The switch 149 operates a solenoid in back of the solenoid 131 (Fig. 8) to pull down the rod 153 and operate the arm 154 carrying the plate 155. The sheet is forced between rollers 141 and 145, the latter of which is pressed against the former by the pivoted journal arm 137 which is indrawn to the left (Fig. 8) by spring 156. The sheet is again folded by passing between the rolls 141 and 145 and is deposited upon conveyor belt 159, which travels around rollers 160 and 161 in the direction of the arrow 162. At the end of its travel the sheet, now twice transversely folded, is carried beneath the nip roll 163 which is preferably rubber covered and is pressed against the belt 159 by the spring 165 which draws the pivoted bracket 164 in which the nip rolls are journaled.

The folded sheet is deposited thereafter on the automatic stacker 166 shown at the extreme right in Fig. 8.

The operation of the switch 149 also operates the stacker mechanism, so that on each passage of a sheet the stacker mechanism will operate but to stack the sheet which has previously operated the switch. That is, there is a lapse between the time when the switch operates until the sheet operating it reaches the stacker so that the following sheet causes the stacking of the sheet previously deposited.

The stacker comprises a platform 170 which is raised and lowered in one cycle of operation by a crank arm 171 and link 172 when the clutch mechanism 173 is operated by the solenoid 174 and core 175. The solenoid is operated by the switch 149 and the operation of the clutch by it is just the same as that of the clutch previously described in the operation of the longitudinal fold plates.

The platform 170 is therefore raised by the shaft 172 when the operating cycle begins.

Mounted over the platform but pivoted at the side are a group of uniformly spaced bell crank-like levers 173. These are thin arms which are aligned with slots in the platform so the platform can be raised above the arms. The bell crank levers are spring tensioned downward so that the arms are normally in a horizontal position.

The sheet deposited on the platform covers the slots so that as the platform comes to the level of the arms of the lever 173, the arms are raised until they clear the platform and drop back to a horizontal position. They are therefore under the slots on the platform in this position so that when the platform drops back, the sheet on it and others which were on the arms are deposited on the arms, with the last sheet at the bottom of the stack.

In Fig. 12 there is shown a mechanism which may be used in connection with the machine. This includes a pair of feed rollers 180 and 181, which are held in contact by means of a spring 182. These feed rollers take the sheet from the conveyor 24 after it has been folded and send it up an inclined guide 183 to a pair of ironing rollers 184 and 185, which are held together in compression by the spring 186. The roller 185 may be a steam roller or heated by other means if desired. The ironed sheet leaves the ironer

over the guide 187 and is again deposited on the belt 24.

I claim:

1. Means for effecting parallel folds of sheet material comprising a stationary central plate and side plates all having cooperating straight edges which are disposed substantially mutually parallel, the plates occupying parallel planes with the side plates being in substantially the same plane and the central plate in a plane below that of the side plate, means for feeding and directing the sheet material so that a portion thereof underlies the central plate and other portions overlie the side plates and means for moving the side plates within their respective planes laterally in phased reciprocal motion over the central plate and returning them to their normal side positions for effecting a lengthwise fold of the sheet material.
2. Means for effecting parallel folds of sheet material comprising a stationary central plate and side plates, the plates occupying parallel planes with the side plates being in substantially the same plane and the central plate in a plane below that of the side plates, means for feeding and directing the sheet material so that a portion thereof will underlie the central plate and other portions overlie the side plates, the central and side plates having edges extending in the direction of the feed of the sheet material, and means for moving said side plates in phased reciprocal motion within their respective planes over a portion of the central plate and returning them to their side positions.
3. Means for effecting parallel folds of sheet material comprising a stationary central plate and side plates positioned substantially parallel to one another and the central plate but at slightly different levels above the central plate, means for feeding and directing the sheet material so that a portion thereof will underlie the central plate and other portions overlie the side plates, means for alternately moving the side plates laterally within their respective planes over a portion of the central plate and returning them to their side positions for effecting a lengthwise fold of the sheet material.
4. Means for effecting parallel folds of sheet material comprising a stationary central plate and side plates all having cooperating straight edges, said plates being positioned substantially parallel to one another but with the side plates at slightly different levels above the central plate, means for feeding and directing the sheet material so that a portion thereof underlies the central plate and other portions overlie the side plates, means for alternately moving first the lower to said side plates and the upper each within their respective planes laterally from the side to a position over the central plate and then returning them to their normal positions, the movement of the upper side plate inwardly approximately following the movement of the lower side plate outwardly of the central plate.
5. Means for effecting parallel folds of sheet material comprising a stationary central plate and side plates all having cooperating straight edges which are disposed mutually parallel, means for feeding and directing the sheet material so that a portion thereof underlies the central plate and other portions overlie the side plates, the plates occupying parallel planes with the side plates being in substantially the same plane and the central plate in a plane below that of the side plates, means for moving the side

plates within their respective planes in phased reciprocal motion over side portions of the central plate and returning them to their side positions and means for holding the sheet in the region of the central plate during the moving of the side plates.

6. Means for effecting parallel folds of sheet material comprising a stationary central plate and side plates, the plates occupying parallel planes with the side plates being in substantially the same plane and the central plate in a plane below that of the side plates, means for feeding and directing the sheet material so that a portion thereof will underlie the central plate and other portions overlie the side plates, the central and side plates having edges extending in the direction of the feed of the sheet material and means for moving the side plates within their respective planes laterally in phased reciprocal motion over side portions of the central plate and returning them to their side positions and means for clamping the sheet to the central plate during the moving of the side plates.

7. Means for effecting parallel folds of sheet material comprising a conveyor belt system having side conveyors and fixed elevating fingers associated therewith and a central nonconveyor region, a central plate and side plates at a level higher than said central plate, said central and side plates being positioned as extensions of the nonconveyor region and the side conveyors respectively with said elevating fingers extending from said side conveyors upwards to said side plates whereby the sheet material will be raised at the sides by the elevating fingers over the side plates and in the center remain under the central plate, and means for moving the side plates laterally in phased reciprocal motion over the central plate and returning them to their normal side position for effecting a lengthwise fold of the sheet material, said central and side plates all having cooperating straight edges which are disposed mutually parallel.

8. Means for effecting parallel folds of sheet material comprising a conveyor belt system having side conveyors and fixed elevating fingers associated therewith and a central nonconveyor region, a central plate and side plates at a level higher than said central plate, said central and side plates being positioned as extensions of the nonconveyor region and the side conveyors respectively with said elevating fingers extending from said side conveyors upwards to said side plates whereby the sheet material will be raised at the sides by the elevating fingers over the side plates and in the center remain under the central plate, one of said side plates being at a level lower than the other side plate and means for alternately moving first the lower of the side plates and then the upper laterally from the side to a position over the central plate and then returning them to their normal side position, the movement of the upper plate inward approximately following the movement of the lower plate outward of the central plate, said central and side plates all having cooperating straight edges which are disposed mutually parallel.

9. Means for effecting parallel folds of sheet material comprising a conveyor belt system having side conveyors and fixed elevating fingers associated therewith and a central nonconveyor region, a central plate and side plates at a level higher than said central plate, said central and side plates being positioned as extensions of the

nonconveyor region and the side conveyors respectively with said elevating fingers extending from said side conveyors upwards to said side plates whereby the sheet material will be raised at the sides by the elevating fingers over the side plates and in the center remain under the central plate, and means for moving the side plates laterally in phased reciprocal motion over the central plate and returning them to their normal side position for effecting a lengthwise fold of the sheet material, and a conveyor belt positioned beneath the central plate and adapted to contact with the material thereunder to moving the sheet after folding from said plate, said central and side plates all having cooperating straight edges which are disposed mutually parallel.

10. Means for effecting parallel folds of sheet material comprising a stationary central plate and side plates the plates occupying parallel planes with the side plates being in substantially the same planes and the central plate being below that of the side plates, means for feeding and directing the sheet material so that a portion thereof will underlie the central plate and other portions overlie the side plates, the central and side plates having edges extending in the direction of feed of the sheet material, means for moving the side plates laterally in phased reciprocal motion over the central plate and returning them to their normal side position for effecting a lengthwise fold of the sheet material and control means operated when the sheet material has reached the desired position for beginning the movement of said side plates.

11. Means for effecting parallel folds of sheet material comprising a fixed central plate and side plates all having cooperating straight edges which are disposed mutually parallel, means for feeding the sheet material under the central plate and over the side plates, means for moving the side plates laterally in phased reciprocal motion over the central plate and returning them to their normal side position for effecting a lengthwise fold of the sheet material, electrical control means and clutch elements operated thereby, an electrical power means adapted to be coupled through said clutch for operating the means for moving said plates, and means for operating said electrical control means when the sheet material has reached the desired position for operating the clutch to couple said electrical power means for beginning the movement of said plates.

12. Means for effecting parallel folds of sheet material comprising a fixed central plate and side plates all having cooperating straight edges which are disposed mutually parallel, means for feeding the sheet material under the central plate and over the side plates, means for moving the side plates laterally in phased reciprocal motion over the central plate and returning them to their normal side position for effecting a lengthwise fold of the sheet material, a photoelectric cell and beam arranged to be interrupted by the sheet material as it begins to pass in the region of said central and side plates, and means controlled and timed after the interruption has ceased for beginning said movement of said side plates when the sheet material has come into a position so that a portion thereof will underlie the central plate and other portions overlie the side plates.

13. Means for effecting parallel folds of sheet material comprising a fixed central plate and

side plates all having cooperating straight edges which are disposed mutually parallel, means for feeding and directing the sheet material so that a portion thereof underlies the central plate and other portions overlie the side plates the plates occupying parallel planes with the side plates in substantially the same plane and the central plate in a plane below that of the side plates, the central and side plates having edges extending in the direction of the feed of the sheet material, and means for moving the side plates within their respective planes laterally in phased reciprocal motion over the central plate and returning them to their normal side position for effecting a lengthwise fold of the sheet material, including a pair of vertical drive shafts having an operating clutch connected therewith positioned one under each of said plates, a crank arm and link for each of said side plates operatively connected thereto and to said drive shafts, and control means operative when the sheet is in the desired position for operating said clutch for moving said side plates.

14. Means for effecting parallel folds of sheet material comprising a conveyor belt system having side conveyors and fixed elevating fingers associated therewith and a central nonconveyor region, a central plate and side plates at a level higher than said central plate, said central and side plates being positioned as extensions of the nonconveyor region and the side conveyors respectively with said elevating fingers extending from said side conveyors upwards to said side plates whereby the sheet material will be raised at the sides by the elevating fingers over the side plates and in the center remain under the central plate, and means for moving the side plates laterally in phased reciprocal motion over the central plate and returning them to their normal side position for effecting a lengthwise fold of the sheet material, including a pair of vertical drive shafts having an operating clutch connected therewith positioned one under each of said plates, a crank arm and link for each of said side plates operatively connected thereto and to said drive shafts and control means operative when the sheet has reached the desired position for operating said clutches for moving said side plates, said central and side plates all having cooperating straight edges which are disposed mutually parallel.

15. Means for effecting parallel folds of sheet material comprising a conveyor belt system having side conveyors and fixed elevating fingers associated therewith and a central nonconveyor region, a central plate and side plates at a level higher than said central plate, said central and side plates being positioned as extensions of the nonconveyor region and the side conveyors respectively with said elevating fingers extending from said side conveyors upwards to said side plates means mounting said side plates in planes just above one another and above the central plate, including a pair of supporting rods extending transversely beneath the plates having sliding sleeves thereon and means mounting said side plates to said sleeves at the outer side region of said plates whereby said side plates may be moved in positions over one another and above the central plate without interference, and means for moving the side plates laterally in phased reciprocal motion over the central plate and returning them to their normal side positions for effecting a lengthwise fold of the sheet material, said central and side plates all having

cooperating straight edges which are disposed mutually parallel.

16. Means for effecting parallel folds of sheet material comprising a conveyor belt system having side conveyors and fixed elevating fingers associated therewith and a central nonconveyor region, a central plate and side plates at a level higher than said central plate, said central and side plates being positioned as extensions of the nonconveyor region and the side conveyors respectively with said elevating fingers extending from said side conveyors upwards to said side plates a frame extending over and across the conveyor belt, means flexibly supporting said central plate at the forward end from said frame, a second conveyor belt positioned just beneath said central plate on which the other end of said central plate rests lightly, means for moving the side plates laterally in phased reciprocal motion over the central plate and returning them to their normal side position for effecting a lengthwise fold of the sheet material, said second conveyor belt acting to carry said folded sheet off said central plate after the folding, said central and side plates all having cooperating straight edges which are disposed mutually parallel.

17. Means for effecting a lengthwise fold in a sheet material comprising a movable plate and a stationary plate each occupying parallel planes side by side and the movable plate being at a level above that of the level of the stationary plate, means for feeding and directing the sheet material in a lengthwise direction so that a portion thereof will underlie the stationary plate and the other portion will overlie the movable plate and means for moving the movable plate within its respective plane over a portion of the stationary plate and returning the same to its side position whereby a lengthwise fold of the sheet material will be made.

18. Means for effecting parallel folds of sheet material comprising a fixed central plate and side plates, the plates occupying parallel planes with the side plates being in substantially the same plane and the central plate in a plane below that of the side plates, means for feeding and directing the sheet material so that a portion thereof will underlie the central plate and other portions overlie the side plates the central and side plates having edges extending in the direction of the feed of the sheet material, means for moving the side plates laterally in phased reciprocal motion over the central plate and returning them to their normal side position for effecting a lengthwise fold of the sheet material, and a conveyor positioned beneath the central plate and in contact therewith for continuing the forward movement of the sheet after the lengthwise folds have been made.

19. Means for effecting parallel folds of sheet material comprising a conveyor belt system, a fixed central plate and side plates positioned above the level of said central plate and serving as a continuation of said conveyor belt system with a plurality of elevating fingers for conducting the material over said side plates, said sheet material normally progressing under said central plate, means for moving the side plates laterally in phased reciprocal motion over the central plate and returning them to their normal side positions for effecting a lengthwise fold of the sheet material, and means for conveying the sheet material off of said central plate.

20. Means for effecting parallel folds of sheet material comprising a fixed central plate and

side plates, the plates occupying parallel planes with the side plates being in substantially the same plane and the central plate in a plane below that of the side plates means for feeding and directing the sheet material so that a portion thereof will underlie the central plate and other portions overlie the side plates the central and side plates having edges extending in the direction of the feed of the sheet material, means for moving the side plates laterally in phased reciprocal motion over the central plate and returning them to their normal side position for effecting a lengthwise fold of the sheet material, and means for conveying the folded sheet away from the central plate.

ROBERT L. SJOSTROM.
